UNITED STATES PATENT OFFICE

CARL E. HALLEN, OF CHICAGO, ILLINOIS, ASSIGNOR TO JOHN B. CROFOOT, OF MOUNT
PROSPECT, ILLINOIS

HOLDING FRAME FOR STAPLES

Application filed September 18, 1930. Serial No. 482,672.

This invention relates to a holding frame for staples whereby a plurality of loose staples may be maintained in position for transportation and handling. An object of the invention is the provision of an improved staple holding frame having capacity for resiliently maintaining a series or row of loose staples in position in such manner that they will not be subject to disarrangement, loss or mutilation, and will be available for subsequent use in a stapling device, and suitably arranged for engagement by the feeding mechanism of a stapling device. The invention is particularly adapted for use in connection with round or elliptical wire staples such as are commonly used in securing together sheets of paper, although it is to be understood that the device is not restricted to this use. Different devices and expedients have been employed for the provision of staple holding frames, which can be cheaply manufactured and which serve to maintain a row of staples in alignment for subsequent use in a stapling device, but these articles have been found objectionable because the staples would not be maintained in proper position when subjected to shipment and handling, and staples would become entirely separated from the holder in many instances.

It is the aim of the present invention, therefore, to provide a simple yet durable device, which is economical to manufacture, and which is highly efficient for the purpose, and which is adapted to effectively maintain a series of staples in alignment during shipment and handling, but which readily permits the successive discharge or release of the staples when ultimately incorporated in a stapling device.

Other objects will appear hereinafter. The invention consists in the combinations and arrangements of parts hereinafter described and claimed.

The invention will be best understood by reference to the accompanying drawings forming a part of this specification, and in which:

Fig. 1 is a perspective view of the device of the invention showing a row of staples in engaged position;

Fig. 2 is a plan view with portions broken away;

Fig. 3 is a side elevational view taken from the right of Fig. 1; and

Fig. 4 is an enlarged sectional view taken on the line 4-4 of Fig. 3.

As illustrated in the drawings, the preferred embodiment of the invention comprises a frame composed of a sheet of metal of channel shape in general cross-sectional outline, comprising a main plate portion 6, side flange 7, and opposite side flange 8. Flanges 7 and 8 are disposed in parallel planes whereby the portions stated will contact with and conform to the shape of a staple to be held, as shown in Fig. 4. Each staple 9 comprises an upper transverse portion 10 and depending parallel prongs 11 and 12, the parallel relationship of the prongs being the preferred construction because each prong is disposed perpendicular to the main transverse portion 10, and when the latter receives an impact in the stapling device, the prongs 11 and 12 are driven through the sheets of paper or other material to be attached and clenched on the opposite side. The holding frame may be composed of tin to lessen the cost of manufacture, and to provide resilient engagement on the outer surface portion of a row of staples, the extension of flange portion 8 is bent to provide a relatively narrow horizontal portion 13. The metal is then bent upwardly to provide a wall 14 spaced from flange 8 to provide a longitudinal channel for receiving prongs 11 of a row of staples. In the preferred embodiment illustrated, the metal is then bent transversely and slightly downward to provide an engaging strip 15 adapted to resiliently contact with the transverse portions 10 of an aligned row of staples, as shown in the drawings. The inherent resiliency of the metal employed adequately maintains the staples in position to prevent dislodging during ordinary shipping and handling, but to secure more positive engagement, the engaging strip 15 is provided with a longitudinally extending depression 16 whereby the lower surface of the

depressed portion will engage the staples and thus uniform engagement is effected.

As an additional precaution against staples becoming displaced endwise, the top engaging strip 15 is provided at each end with a confining indented portion 17 which projects downwardly in the path of the staples and requires greater displacement of strip 15 for the passage of the staple. It is to be understood, however, that the device is adapted to be incorporated in a staple machine, and therefore the retarding action of either strip 15 or the indented portions 17 is not sufficient to interfere with the operation of a follower block and the successive ejection of staples from the frame through the machine.

For the purpose of facilitating the introduction of a follower block when used with a stapling machine, the strip 15 preferably has an upwardly flared portion 18 at each end. Also, flange 7 may be provided with outwardly deflected portions 19 formed by merely slitting the flange and pressing the slitted portion outwardly to provide additional yieldable staple retaining means.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A staple holding frame comprising a sheet of metal bent to form a longitudinally extending channel shaped portion having a top plate portion and lateral parallel flanges for the reception of a row of loose staples, one of said flanges turned upwardly and inwardly to provide a staple engaging portion, a longitudinally extending depression formed in said upwardly and inwardly turned portion, and a staple retaining indentation provided adjacent the ends of said inwardly turned portion.

2. A staple holding frame comprising a sheet of metal bent to form a longitudinally extending channel shaped portion having a top plate portion and lateral parallel flanges for the reception of a row of loose staples, one of said flanges turned upwardly and inwardly to provide a staple engaging portion, a longitudinally extending depression formed in said upwardly and inwardly turned portion, and outwardly deflected portions provided adjacent the ends of the opposite flange.

3. A staple holding frame comprising a sheet of metal bent to form a longitudinally extending channel shaped portion having a

top plate portion and lateral parallel flanges for the reception of a row of loose staples, one of said flanges turned upwardly and inwardly to provide a staple engaging portion, a longitudinally extending depression formed in said upwardly and inwardly turned portion, outwardly deflected portions provided adjacent the ends of the opposite flange, and a staple retaining indentation provided adjacent the ends of said inwardly turned portion.

In testimony whereof I have signed my name to this specification in the presence of two subscribing witnesses.

CARL E. HALLEN.
